LIGHT-SENSITIVE CELL

Arthur W. Carpenter, New York, N. Y., assignor
to United Research Corporation, New York,
N. Y., a corporation of Delaware

Application September 20, 1930, Serial No. 483,263

1 Claim. (Cl. 201—63)

This invention relates to light-sensitive cells, and particularly to means for increasing the response of a cell to a given light intensity.

In any light-sensitive cell system it is desirable that an efficient utilization of the incident light be obtained in order to secure a substantial electrical output from the cell and to secure reduced losses therein for a given value of illumination.

An object of this invention is to increase the response of a light-sensitive cell to a given light intensity.

Another object is to avoid the loss of response in a light-sensitive cell from unabsorbed light when the sensitive layer is thin and not opaque.

Still another object is to combine in a light-sensitive cell a plurality of sensitive members responsive to the same beam of light.

A further object is to combine in a light-sensitive cell a light-sensitive layer and a reflector member.

Still further objects are to combine a plurality of separated cell members into a single structure, responsive to a single light beam, and to utilize a member having electrodes and sensitive layers on both sides.

In the operation of light-sensitive cells it is found that when the thickness of the coating of sensitive material is made of such a value, that is, thin enough, to secure the maximum ratio between the average resistance of the cell, and the change in resistance with a given intensity of illumination, a substantial portion of the light incident upon the cell passes through the sensitive material, because of the transparency inherent in a thin coating. This light is lost for the production of response in the usual type of light-sensitive cell.

This invention provides means for utilizing this light to produce an added response in the light-sensitive cell by such means as reflecting the light back into the sensitive material, using a plurality of layers of sensitive material and other methods.

These objects are thus accomplished by causing a beam of light to be successively partially absorbed and converted into electrical response.

Other objects and structural details of the invention will be apparent from the following description when read in connection with the accompanying drawing wherein:

Fig. 1 is a view in vertical section of a light-sensitive cell according to the invention, embodying a reflecting means.

Fig. 2 is a view also in vertical section of a

light-sensitive cell embodying a plurality of layers of sensitive material.

Fig. 3 is a view in vertical section of a light-sensitive cell embodying a plurality of layers of light-sensitive material adapted to multiple reflection of light between various surfaces, and

Fig. 4 is a view in vertical section along the lines 4—4 of the cell shown in Fig. 3.

Referring to the figures, particularly to Fig. 1, a glass plate or slip 1 is provided, upon which is mounted a pair of electrodes 2 and 3, preferably of platinum and adherent to the glass 1.

The electrodes are provided with interdigitated portions over which is positioned a layer of photo-sensitive material 4 such as selenium. The sensitive material 4 is covered and protected by a cup member 5 held in place by cement 6.

Within the cup 5 is positioned a quantity of appropriate drying material such as calcium chloride 7 for aiding in the protection of the light sensitive material 4, and also a reflector means which may conveniently consist of glass or other suitable material 8 upon which is a reflecting surface 9.

If the member 8 is of glass, the reflecting surface 9 may be a silver film on the side opposite to the sensitive material 4. If the material 8 is an opaque substance as steel, etc., the reflecting surface 9 should obviously be upon the same side as the sensitive material 4.

The reflector member may be held in position by the cement 10 as shown, or may be simply laid loosely within the cup member 5 upon the drying material 7.

In any event, care should be taken that the cement 10 does not produce an air tight separating partition between the drying material 7 and the sensitive material 4.

In this embodiment, when a ray of light enters the cell, a portion of the light may be absorbed by the sensitive material 4 to produce the desired electrical response, while another portion b may pass through the sensitive material 4.

The portion b is, however, reflected back by the reflector 8, and is incident upon the sensitive material 4 on the reverse side from the portion a. Most of the reflected portion b is then absorbed in the sensitive material to produce an added effect.

Furthermore, because of the inherent surface reflection of glass, any small parts of reflected light b which are not completely absorbed may be re-reflected at the glass to air boundary for further minor influences upon the light-sensitive material.

This device thus increases the effect of a given light intensity upon a light-sensitive cell, and raises the output ratio.

Alternatively, a second layer of light-sensitive

material may be provided to receive the transmitted light. Referring to Figure 2, a plurality of glass plates or slips 11 and 12 may be provided upon which are positioned two pairs of electrodes 14 and 15, and 16 and 17. These pairs of electrodes, which may desirably be of platinum, are arranged with interdigitated portions as described in connection with Fig. 1, which portions are also covered with layers of light-sensitive material 18 and 19. An annular member 21, which may conveniently be a short length of glass tubing is provided and attached by cement 22 in such a position as to bring the sensitive layers 18 and 19 within the annular member. Drying material 23 is also provided as before. Connection may be made to the respective electrodes in any convenient way, as by spring clamps or soldered connections or other means as desired.

In the operation of this embodiment, any light incident upon one of the light-sensitive layers or units which is not absorbed, but transmitted, is received by the other of the layers, to produce an added effect in the circuit, if the two units are connected together. Alternatively, the second unit may be utilized to produce a second output in a separate circuit, for such uses as monitoring or other purposes.

Alternatively the electrodes and layer of sensitive material may be positioned upon opposite sides of a glass member, and the incident light applied to an edge of the glass member. Multiple internal reflection is then utilized to obtain a maximum light action on the sensitive material. This embodiment is shown in Fig. 3 in which a glass plate or slip 25 is provided as before, and an auxiliary glass plate or slip 26, or a plurality of such plates as shown, may be provided with interdigitated pairs of electrodes 27 and 28 preferably of platinum upon opposite sides. The interdigitated portions are covered with layers of sensitive material 31 and 32. The auxiliary plate members 26 may be cemented to the plate member 25 in any convenient way as by Canada Balsam or other suitable cementing means. Alternatively, the auxiliary plates may be merely held in contact, although a loss of light may occur under these conditions from surface reflections.

It is desirable that the plate members 26 be attached at an angle as shown, in order to provide a maximum area for the entrance of light, and for similar reasons the plurality of auxiliary plates may be used. A protecting cup member 33 is desirably attached to the plate 25, over the plates 26, by means of cement 34, and the drying material 35 is included within the cup 33 as before.

5

In the operation of this cell, the light ray enters the cell from the plate 25 as shown, and by a plurality of surface reflections at the interface between the glass and the sensitive material, it is reflected back and forth in the glass plate, and is thus incident a plurality of times upon the light-sensitive material. In this way a maximum utilization of the incident light is obtained, and a minimum amount of light is wasted from transmission and other losses.

10

In this embodiment as before, connection may be made to the electrodes 27 and 28 in any convenient way, as by spring clamps, or soldered leads, 36 which may be brought through the cup member 33 in any suitable manner.

15

In this invention thus provides a simple and convenient means, including various methods of utilizing reflecting means and a plurality of sensitive coatings for the better and more efficient utilization of light in the light-sensitive cell, to produce a greater response ratio, thereby obtaining a more efficient and effective cell, as well as a new and useful cell construction.

20

While the above disclosure shows but a limited number of embodiments of the invention, it is possible to produce still further embodiments without departing from the inventive concept herein disclosed and it is therefore desired that only such limitations shall be imposed upon the appended claim as are stated therein or required by the prior art.

25

The invention claimed is:

A light-sensitive cell comprising a plurality of pairs of electrodes and layers of sensitive material cooperating therewith, in cooperative relation to a single transparent support said electrodes comprising means adapted to reflect light to and between said sensitive layers.
